AWNNG OR JALOUSIE

Orman O. McKinley, Indianapolis, Ind.

Application May 3, 1946, Serial No. 667,163

6 Claims. (Cl. 20—57.5)

1

The present invention relates to an awning or jalousie, the construction of which is such that it is adapted to be integrated from metal parts. The device comprises a frame having hinged thereto a plurality of louvers which are adjustable, as a group, to vary the degree of admission of light through the device. The invention is primarily concerned with the production of such devices which shall be relatively inexpensive, simple in construction, readily manipulable, capable of easy installation and dismounting, and relatively free from damaging effects of wear.

Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a front elevation of an awning constructed in accordance with the present invention, associated with a window;

Fig. 2 is an end elevation of the awning of Fig. 1, the window frame with which it is associated being shown in transverse section;

Fig. 3 is a fragmental enlarged perspective view of a portion of the awning, parts being broken away for clarity of illustration;

Fig. 4 is a transverse section taken substantially on the line 4—4 of Fig. 3;

Fig. 5 is a further enlarged fragmental end elevation of a detail;

Fig. 6 is a perspective view of a rope catch advantageously usable in connection with my invention;

Fig. 7 is an enlarged elevation of a detail; and

Fig. 8 is a view similar to Fig. 4, and showing an adapter intended for use when the louvered structure is installed as a jalousie.

Referring more particularly to the drawings, it will be seen that the device of the present invention comprises a pair of parallel bars 10 and 10'. Each of these bars may preferably comprise an aluminum extrusion formed to provide a laterally projecting protrusion 11 projecting beyond the main body of the bar and defining a pair of tables 12 and 13, lying substantially in a common plane, upon opposite sides of said protrusion. Centrally formed in the bar 10 is a longitudinally extending, substantially cylindrical trackway 14 with which communicates a

2

slot 15, opening through the protrusion 11, and having a width less than the diameter of said trackway. The trackway 14 will preferably run the full length of the bar 10, as will the slot 15.

Reciprocably mounted in the trackway 14 is a rod 16; and a screw 17, entering the slot 15, provides a pivotal mounting upon the rod 16 for one end of a link 18. Said screw likewise secures 10 to said rod 16 a frame 19 providing a journal mounting for a pulley 20.

A bracket 21 is pivoted at 22 upon the table 12 of the bar 10; and it will be seen that the arrangement is such that the link 18 is disposed 15 in a plane sufficiently spaced from the table 12 to clear such an element as the bracket 21 supported upon the table. That end of the link 18 remote from the screw 17 is pivotally connected, as at 24, to the bracket 21 intermediate the ends 20 thereof.

At a point spaced below the pivotal point 22, a second bracket 21' is pivotally mounted upon the table 12; and a second link 18' has one end connected to the rod 16 below the point of connection of the link 18 thereto, and its other end pivotally connected to the bracket 21' intermediate the ends thereof. Further such brackets and links are mounted upon the bar 10 and operatively connected with the rod 16 in a series of any suitable extent.

Upon the bar 10' there are mounted, in a similar fashion, brackets corresponding to the brackets just described; and preferably links corresponding to the links 18 and 18' will be operatively connected with said brackets on the bar 30 10' and with a rod guided in the bar 10'. At any rate, each bracket on the bar 10 will find a mate correspondingly positioned on the bar 10'.

Within the upper end of the trackway 14 is 40 confined a coiled spring 26 which continuously resiliently urges the rod 16 to move downwardly in said trackway. Suitably fixed to the bar 10 is a bracket 23 to which is fixedly connected one end 27 of a rope or cord 28 which leads 45 from said bracket, beneath the pulley 20, and thence through a suitable fitting 29 to and through the window frame. A mating cord 28' may lead to a similar fitting upon the rod guided in the bar 10'.

Fixed to the bracket 21 and to its mate carried by the bar 10' is a louver slat 30. Said slat will preferably be formed of sheet metal, and its forward or lower end will be bent downwardly as at 31, while its rearward end will be bent upwardly as at 32. Fixed to the bracket 21' and

3

to its mate on the bar 10' is a correspondingly shaped louver slat 30' having its front edge turned downwardly as at 31' and its rear edge turned upwardly as at 32'. Obviously, when the brackets are swung downwardly, the upturned edge 32' of the slat 30' will overlap the down-turned edge 31' of the slat 30, whereby a very tight closure will be provided against light, breezes, or rain. Fixed to the upper ends of the bars 10 and 10' is an escutcheon slat 33 whose lower edge 34 is inturned for cooperation with the edge 32 of the slat 30.

Of course, similar slats are carried by succeeding pairs of brackets.

The cords 28 and 28' pass through the window frame and thence through a fitting 35, whence they extend downwardly to and through a catch fitting 36. Such fitting is illustrated in detail in Fig. 6.

The fitting 36 comprises a housing 37, which may preferably be formed of sheet metal, and which comprises a rear wall 38 adapted to be suitably secured to the window frame, and a front wall 46. A pivot pin 39, journaled in the side walls of the housing 37, mounts a catch block 40. The rear wall 38 of the housing 37 is disposed in the path of counter-clockwise movement of the end 41 of the block 40; and a coiled spring 43 is wrapped about the pin 39, one end 44 engaging the end 41 of the block 40, and the other end 45 thereof abutting against the wall 46, whereby said spring urges the end 41 of the block toward engagement with the wall 38 of the housing. The wall 46 of the housing is slotted, as at 47, to permit protrusion of the end 42 of the block therethrough. The ropes 28 and 28' are threaded through the housing 37 between the end 41 of the block 40 and the wall 38. Obviously, the construction is such that when a downward force is applied to the ropes, they may move smoothly past the end 41 of the block 40; but when said ropes are released, the spring 43 will crowd the end 41 of the block 40 against said ropes; and any tendency of the ropes to move upwardly will merely increase the clamping grip of the block end 41 upon said ropes. When it is desired to permit the ropes to move upwardly, the protruding end 42 of the block may be pressed inwardly, thus moving the end 41 of said block out of engagement with the ropes.

In Fig. 2, I have shown brackets 48 secured to the window frame and to the lower ends of the bars 10, to hold said lower ends of said bars outwardly from the window. If it is desired to use the illustrated structure as a jalousie, the arrangement of Fig. 3 is installed. A bracket 49 is associated with each of the arms 10 and 10'. Each bracket 49 comprises an arm 50 adapted to be secured, by means of a screw 51, to the window frame 52; and a second arm 53 adapted to engage the table 13 of the associated bar. A thumb screw 54 penetrates said arm 53 and is adapted to be threaded into a suitable opening 55 in the bar 10, thus securing the lower end of the bar to the window frame.

At the upper end of each bar may be fixed a hinge bracket 56 suitably connectible to a mating hinge bracket 57 fixed to the window frame.

I claim as my invention:

1. An awning or jalousie comprising a pair of bars, each provided at its upper end with hinge means adapted to be connected, on a common horizontal axis, for swinging movement above a window frame, a plurality of brackets hinged to each bar at spaced points along its length for

4

swinging movement about axes parallel with said common axis, the hinged connection for each bracket being substantially at one end of said bracket and each bracket on one bar having a mate in a corresponding position on the other bar, a link for each bracket on one bar, each link having one end pivotally connected to its bracket intermediate the ends thereof and at a point remote from the hinged connection of its bracket, and each link further having its other end guided on said bar for movement therealong, means engaging the last-named ends of said links and shiftable to move the same along said bar, and a louvre plate mounted on and connecting each bracket with its mate.

2. An awning or jalousie comprising a pair of parallel trackways, a plurality of brackets, means engaging an end of each bracket and pivotally mounting said brackets at spaced points on each of said trackways, each bracket on one trackway having a mate mounted on the other trackway to swing about a common axis therewith, a slat carried by and connecting each bracket with its mate, means guided by each trackway for movement therealong, and a link for each bracket, each link having one end pivoted to its bracket intermediate the ends thereof and having its other end operatively connected with the means guided by its trackway.

3. An awning or jalousie comprising a pair of parallel trackways, a plurality of brackets pivotally mounted at spaced points on each of said trackways, each bracket on one trackway having a mate mounted on the other trackway to swing about a common axis therewith, a slat carried by and connecting each bracket with its mate, means guided by each trackway for movement therealong, spring means urging said guided means to move in one direction along each trackway, manually manipulable means for shifting said guided means in the opposite direction against the tendency of said spring means, and a link for each bracket, each link having one end pivoted to its bracket intermediate the ends thereof and having its other end operatively connected with the means guided by its trackway.

4. In a device of the class described, an elongated body formed with a central, laterally-projecting, longitudinally-extending protrusion from one side wall thereof, defining a table in a plane inset from the surface of said protrusion, a substantially cylindrical trackway formed in said body and extending longitudinally thereof, a slot opening from said trackway laterally through said protrusion, an element guided in said trackway, a member movable substantially in contact with the outermost surface of said protrusion, means entering said slot and connecting said member with said element, and means pivotally secured to said table, said member being spaced from said table sufficiently to clear said last-named means.

5. An awning or jalousie comprising a pair of parallel trackways, a plurality of brackets pivotally mounted at spaced points on each of said trackways, each bracket on one trackway having a mate mounted on the other trackway to swing about a common axis therewith, a slat carried by and connecting each bracket with its mate, means guided by one trackway for movement therealong, spring means urging said guided means to move in one direction along its trackway, a link for each bracket on said one trackway, each link having one end pivoted to its bracket intermediate the ends thereof and having

ing its other end operatively connected with said guided means, a sheave fixedly associated with said guided means, and flexible means having one end fixed, passing about said sheave, and extending to a point for manipulation, for shifting said guided means against the tendency of said spring means.

6. An awning or jalousie comprising a pair of parallel trackways, a plurality of brackets pivotally mounted at spaced points on each of said trackways, each bracket on one trackway having a mate mounted on the other trackway to swing about a common axis therewith, a slat carried by and connecting each bracket with its mate, means guided by one trackway for movement therealong, spring means urging said guided means to move in one direction along its trackway, a link for each bracket on said one trackway, each link having one end pivoted to its bracket intermediate the ends thereof and having its other end operatively connected with said guided means, a sheave fixedly associated with said guided means, flexible means having one end fixed, passing about said sheave, and extending to a point for manipulation, for shifting said guided means against the tendency of said spring means, and a gripping device operatively

associated with said flexible means for automatically gripping said flexible means to hold the same against movement under the influence of said spring means.
